UNITED STATES PATENT OFFICE.

CARL F. HETTINGER, OF BOSTON, MASSACHUSETTS.

ROTARY COMPRESSOR.

1,136,957.

Specification of Letters Patent.

Patented Apr. 27, 1915.

Application filed January 6, 1914. Serial No. 810,665.

To all whom it may concern:

Be it known that I, CARL F. HETTINGER, a citizen of the United States, residing in Boston, in the county of Suffolk and State of Massachusetts, have invented an Improvement in Rotary Compressors, of which the following description, in connection with the accompanying drawings, is a specification, like characters on the drawings representing like parts.

This invention relates to a rotary compressor especially designed and adapted among other uses, to be employed in refrigerating apparatus for compressing the gaseous refrigerent used therein, which may be ammonia, carbon dioxide, sulfur dioxide or other suitable gas or vapor.

The present invention has for its object to provide a simple, efficient and inexpensive rotary compressor, especially adapted for the purpose specified. To this end, the rotary compressor is preferably made as herein shown and is provided with a cylindrical casing having a fluid inlet at one end and a fluid outlet at its opposite end, and containing within it a rotor, comprising a conical center member or body portion and a helical compressing member or worm, of a diameter equal to the internal diameter of the cylindrical casing to make contact therewith, and which cooperates with the center or body portion of the rotor to form a helical passage, which extends from the fluid inlet to the fluid outlet of the casing and is of greatest holding capacity or size at the inlet end of the casing, and decreases in size toward the outlet end of said casing, so that in the rotation of the rotor, a substantially large volume of gas admitted into the casing at one end thereof may be forced toward the opposite or outlet end thereof and be subjected to an increasing pressure to compress the same. Provision is made for absorbing the heat generated as the gas is compressed, which may be effected as herein shown by providing the cylindrical casing with a water jacket through which water or other cooling medium is circulated. The fluid outlet port may be controlled by an automatic valve as will be described. These and other features of this invention will be pointed out in the claims at the end of this specification.

The drawing represents in section and elevation one form of compressor embodying this invention.

In the embodiment of the invention herein shown, *a* represents a cylindrical casing, which is provided at its opposite ends with heads *b*, *c*, which are secured fluid tight to said casing by bolts *d* or otherwise.

The casing *a* contains within it a rotor, which comprises in the present instance a conical center member or body portion *10*, having extended from its opposite ends journals *12*, *13*, constituting the shaft for the rotor, and a helical compressing member or worm *14* attached to or forming part of the center member *10*, and of a diameter equal to the internal diameter of the casing, so as to form with the latter and the conical center member, a closed helical passage *15*, which extends in the direction of the length of the rotor from one end of the cylinder to the other, and which decreases in size or capacity from the inlet to the outlet end of the casing.

In the present instance, the apex of the conical center member *10* is located adjacent to the head *b* of the casing, and said head has attached to it one or more fluid inlet pipes *17*, and in the present instance two such pipes are shown, each of which is provided with a hand operated valve *18* and with a check valve *19*.

The base of the conical center member *10* is located adjacent to the cylinder head *c*, which is provided with one or more fluid outlet ports *20*, herein shown as two in number and each normally closed by an automatically operated valve *21*, having its stem *22* encircled by a spring *23*, between a stationary disk *24* and the said valve. The disk *24* is shown as located in a hollow boss *25* on the cylinder head *c*, and said boss is provided with a removable cap *26* and with an outlet pipe *27*. The stem *22* of the valve *21* is provided with a nut *28* to avoid injury to the valve when the latter is closed by its spring *23*. The shaft *12*, *13* of the rotor extends through the cylinder heads and through suitable stuffing boxes *30*, secured to or forming part of said heads and containing suitable packing material *31*, by which leakage of gas out of the cylinder along the shaft is prevented or reduced to a minimum.

The shaft *12*, *13* of the rotor may be rotated in any suitable or well known manner, and it is deemed unnecessary to illustrate the driving mechanism for the rotor, as said mechanism constitutes no part of the present invention.

2
. The gas inlet pipes 17 are designed to be connected with the source of supply for the gas in an expanded condition, such for instance as the expansion coil or chamber of 5 a refrigerating system, and said gas is drawn into the casing of the compressor by the rotor. The expanded gas is forced in the direction of the length of the rotor through the helical passage 15 to the outlet 10 end of the casing, and as the passage 15 decreases in area or size, the gas is compressed and materially diminished in volume by the 15 helical compressing member 14. The compressed gas passes through the outlet port or ports 20 into the hollow bosses 25, and out therefrom through the pipes 27, which may lead to a condenser of known construction and not herein shown.

The heat generated by the compression 20 of the gas on its passage through the compressor is absorbed by a cooling medium, such as water 34, which is circulated through a jacket 35 enveloping the cylindrical casing *a* and provided with an inlet 25 pipe 36 at one end and with an outlet pipe 37 at the other end.

It will be observed that in the rotor herein shown, the gas is forced in the direction of the length of the rotor through a helical 30 passage which decreases in size from the gas inlet to the gas outlet of the compressor, and while I have shown a preferred construction of rotary compressor for accomplishing this result, it is not desired to limit 35 the invention, to the particular construction shown. Furthermore the size of the helical passage may be varied according to the particular degree of compression it is desired to obtain.

40 Claims:

1. In a rotary compressor, in combination, a cylindrical casing provided with a water jacket, and having at one end a head provided with a fluid inlet and at its opposite end a head provided with a fluid outlet, of a rotor located within said casing and separate therefrom and comprising a conical center member journaled in said heads with the apex of said member adjacent the fluid inlet end of said casing, and a helical compressing member attached to said center member to revolve therewith and co-operating with the latter and the said casing to form a helical passage, which decreases in size from the fluid inlet end of the said casing to the fluid outlet end thereof, said helical compressing member making a substantially fluid-tight fit with said casing, substantially as described.
- 55 2. In a rotary compressor, in combination, a casing provided at one end with a fluid inlet and at its other end with a fluid

outlet, and having means for cooling it, of a rotor located within the casing and separate therefrom and comprising a conical 65 center member and a helical compressing member attached to said center member and co-operating with the latter and said casing to form a helical passage which decreases in size from the fluid inlet end of the casing to the fluid outlet end thereof, said helical compressing member making a substantially fluid-tight fit with said casing, substantially as described.

3. In a rotary compressor, in combination, a casing provided with a fluid inlet and with a fluid outlet, a rotor rotatable in said casing, and provided with a passage extended in the direction of the length of the rotor and of a size which decreases from 80 the fluid inlet to the fluid outlet of said casing, said rotor making a substantially fluid-tight fit with said casing.

4. In a rotary compressor, in combination, a casing provided with a fluid inlet 85 and with a fluid outlet, and a rotor rotatable within said casing and making a substantially fluid-tight fit with said casing, one of said parts having a helical passage extended in the direction of the length of 90 the rotor and of a size which decreases from the fluid inlet to the fluid outlet of said casing.

5. In a rotary compressor, in combination, a casing provided with a fluid inlet 95 and with a fluid outlet, and a rotor rotatable in said casing and comprising a conical center member and a helical compressing member which makes a substantially fluid-tight fit with said casing, said rotor 100 being located in the said casing with the apex of the center member adjacent the fluid inlet of the casing, substantially as described.

6. In a rotary compressor, in combination, a casing provided with a fluid inlet 105 and with a fluid outlet, and a rotor within said casing and making a substantially fluid-tight fit with said casing, one of said parts being revoluble with relation to the other 110 and having a helical passage extended in the direction of the length of the rotor and of a size which decreases from the fluid inlet to the fluid outlet of said casing, and means external to said casing for cooling 115 the same.

In testimony whereof, I have signed my name to this specification in the presence of two subscribing witnesses.

CARL F. HETTINGER.
